(57) **CLAIM**

The ornamental design for a bottle, substantially as shown and described.

DESCRIPTION

FIG. 1 is a perspective view of a bottle, showing my design.

FIG. 2 is a front view of the bottle.

FIG. 3 is a rear view of the bottle.

FIG. 4 is a right side view of the bottle.

FIG. 5 is a left side view of the bottle.

FIG. 6 is a top view of the bottle; and,

FIG. 7 is a bottom view of the bottle.

The surface shading and contour lines shown in the drawings represent shading and contours. The stippling on the lower bottom portion of the bottle represents a contrast in appearance.

The broken lines in the drawings depict portions of the bottle that form no part of the claimed design.
